Primary Examiner — Ricky Pham*(74) Attorney, Agent, or Firm* — Lewis Brisbois Bisgaard & Smith, LLP(57) **CLAIM**

The ornamental design for a mixing element, as shown and described.

DESCRIPTION

FIG. 1 is a top front isometric view of the mixing element; FIG. 2 is a top plan view of the mixing element; FIG. 3 is a bottom plan view of the mixing element; FIG. 4 is a right side elevation view of mixing element; FIG. 5 is a left side elevation view of the mixing element; and,

FIG. 6 is a top front isometric of the mixing element positioned within an infant bottle.

The broken line showing of the infant bottle in FIG. 6 is for the purpose of showing context and forms no part of the claimed design.

1 Claim, 4 Drawing Sheets**US D784,760 S**
